ATTORNEY

UNITED STATES PATENT OFFICE

WILLIAM ANDREW MCFARLAND, OF BENA, MINNESOTA

COMBINED TIE PLATE AND RAIL ANCHOR

Application filed July 15, 1927. Serial No. 206,043.

My invention relates to improvements in combined tie plates and rail anchors, and it consists in the combinations, constructions, and arrangements herein described and 5 claimed.

An object of my invention is to provide a combined tie plate and rail anchor which will rigidly hold the rail against lateral or longitudinal displacement.

10 A further object of my invention is to provide a device of the type described which obviates the need of the ordinary tie plate and protects the tie.

15 A further object of my invention is to provide a device of the type described which has novel means for preventing the tie from splitting, this means serving a double function in that it also holds the rail against displacement.

20 A further object of my invention is to provide a device of the type described which acts as a brace for the rail.

25 Other objects and advantages will appear in the following specification, and the novel features of the invention will be particularly pointed out in the appended claim.

My invention is illustrated in the accompanying drawings, forming part of this application, in which

30 Figure 1 is a top plan view of my device as applied to a rail and a tie,

Figure 2 is a section along the line 2—2 of Figure 1,

35 Figure 3 is an end elevation taken substantially along the line 3—3 of Figure 1, and

Figure 4 is a bottom plan view of the device.

In carrying out my invention, I provide an anchor plate 1 having longitudinally extending retaining flanges 2 integral with the bottom surface 3 thereof. Square openings 4, 5, 6, 7 and 8 extend through the anchor plate for receiving track spikes 9. A relatively large rectangular opening 10 extends through the anchor plate 1 and is positioned adjacent the openings 6, 7 and 8.

The upper surface 11 of the plate 1 is provided with an upright or abutment 12 of the shape shown in Figures 1 and 2. The upright 12 is integral with the plate 1 and is

provided with an opening 13 for receiving a track bolt 14.

An anchor 15 is provided with a fluke 16 which is adapted to be received in the opening 10 when the anchor is disposed upon the upper surface 11 of the plate 1. The anchor 15 is provided with an integral upright or brace 17 which has an opening 18 adapted to receive the track bolt 14. The anchor 15 is provided with integral projections or flanges 19 and 20 which provide recesses 21 and 22 for receiving two of the track spikes 9. A square opening 23 extends through the anchor for receiving another of the track spikes 9.

From the foregoing description of the various parts of the device, the operation thereof may be readily understood. The anchor plate 1 is disposed upon a tie 24 so that the retaining flanges 2 extend lengthwise of the tie. In placing the anchor plate in the desired position, it extends beneath a rail 25 which rests upon the upper surface 11 thereof adjacent the upright 12. The rail 25 is provided with an opening 26 for receiving the track bolt 14.

The anchor 15 is then placed upon the upper surface 11 so that the fluke 16 extends within the opening 10 and the upright 17 is positioned adjacent the rail 25. The track bolt 14 is then disposed through the openings 18, 26 and 13 in the upright 17, the rail 25, and the upright 12, respectively. A nut 27 is then disposed upon the track bolt 14 and moved upon the bolt by any suitable wrench, not shown, until the uprights 12 and 17 and the rail 25 are rigidly secured together. The track spikes are then disposed in the openings 4 and 5 and driven into the tie 24, thus rigidly securing the anchor plate to the tie and embedding the retaining flanges 2 in the upper portion of the tie. Additional track spikes 9 are passed through the recess 21, the opening 6, through the recess 22 and the opening 7, through the openings 23 and 8 and are all forced into the tie 24, thus rigidly securing the anchor and the tie plate to the tie.

The retaining flanges 2 are embedded in the tie 24, and in this manner hold the tie against splitting. These flanges also hold

the rail against lateral displacement and co-operate with the track bolt 14 for holding the rail against longitudinal displacement.

The fluke 16 of the anchor 15, as indicated by the dotted lines in Figure 2, is adapted for extending under the rail and is in engagement with the under side of said rail. The base portion of the anchor 15, disposed within the opening 10, is adapted to snugly fit within the opening so that there can be no horizontal movement of the anchor 15 with respect to the anchor plate 1. That part of the base portion constituting the fluke 16 prevents any vertical movement of the anchor 15 with respect to the anchor plate 1 by reason of the weight of the rail holding it in position. Thus it will be seen that there can be no horizontal or vertical movement of the anchor 15 with respect to the plate 1 after the whole is locked together as a unit even though the spikes and the bolt become loosened.

I claim:

The combination with a railway tie and a rail, of a rail anchor comprising a plate disposed between the tie and the rail, said plate being provided with an upwardly projecting flange adapted to abut one side of the rail, a supplementary flange oppositely disposed from said first named flange and adapted to abut the opposite side of said rail, said supplementary flange being provided with a base portion receivable in an opening in said plate, said base portion being provided with a projecting fluke for engaging the under side of the rail, said plate being provided with openings adapted to receive spikes for fastening said plate to the tie, said supplementary flange having an opening adapted to receive a railway spike for fastening said flange to the tie, and fastening means associated with the flanges and the rail for locking the plate, the flanges, and the rail together.

WILLIAM A. McFARLAND.
